SOLOMON DARKESS, OF DEERFIELD, INDIANA.

Letters Patent No. 96,312, dated November 2, 1869.

IMPROVED MILLSTONE-DRIVER.

The Schedule referred to in these Letters Patent and making part of the same.

I, SOLOMON DARKESS, of Deerfield, in the county of Randolph, and State of Indiana, have invented a certain new and improved Jointed Millstone-Driver, of which the following is a specification.

The invention consists of a millstone-driver, (as it is termed,) constructed in three parts, so pivoted together as to permit the central portion to freely adjust itself to the position of the stone independent of the position of the ends.

In the accompanying drawings—

Figure I is a vertical section longitudinally through the driver.

Figure II is a horizontal section, showing a plan of the driver, and manner of wedging the same to the bail.

Like letters of reference designate like parts in each of the figures.

A is the upper, and B the lower millstone;

C is the mill-spindle;

D, the bail or rynd, secured to the eye of the upper stone in the usual manner; and

E, my improved driver, transversely divided into three parts, *e e e*.

These parts are pivoted together, as shown, by which the central portion *e* is permitted to freely turn

independent of the ends *e e*. The central portion has a hole to receive the mill-spindle, to which it is keyed in the ordinary way.

The end-pieces *e e* are recessed to receive the bail, which is fastened therein by wedges. Sufficient space is left between the bail and base of the recess to permit of the required adjustment, in a direction at right angles to the adjustment allowed by the pivot.

When the driver is made rigid in one piece, it has been found extremely difficult to secure it an accurate position to the bail.

By means of my improved construction this difficulty is obviated, as the inequalities of the wedging, and position of the ends, do not affect the central portion, which freely accommodates itself to the position of the stone under all circumstances.

What I claim as my invention, is—

The millstone-driver E, composed of the parts *e e e*, pivoted together, and operating with the bail D, in the manner and for the purpose set forth.

SOLOMON DARKESS.
